CLAIM

The ornamental design for a protective sleeve for an intraoral scanner, as shown and described.

DESCRIPTION

FIG. 1 is a front elevation view of a protective sleeve for an intraoral scanner in accordance with the present invention; FIG. 2 is a back elevation view thereof;

FIG. 3 is a bottom plan view thereof;

FIG. 4 is a top plan view thereof;

FIG. 5 is a right side elevation view thereof;

FIG. 6 is a left side elevation view thereof;

FIG. 7 is a front perspective view thereof;

FIG. 8 is a back perspective view thereof;

FIG. 9 is a front elevation view of a second embodiment of a protective sleeve for an intraoral scanner;

FIG. 10 is a back elevation view thereof;

FIG. 11 is a bottom plan view thereof;

FIG. 12 is a top plan view thereof;

FIG. 13 is a right side elevation view thereof;

FIG. 14 is a left side elevation view thereof;

FIG. 15 is a front perspective view thereof; and,

FIG. 16 is a back perspective view thereof.

The broken lines in the drawings depict portions of the protective sleeve for an intraoral scanner that forms no part of the claimed design.
